UNITED STATES PATENT OFFICE.

PAUL G. TISMER, OF NEW YORK, N. Y.

VALVE.

Specification of Letters Patent. Patented Aug. 26, 1919.

Application filed April 23, 1914. Serial No. 832,928.

To all whom it may concern:

Be it known that I, PAUL G. TISMER, a subject of the German Emperor, residing in the borough of Manhattan, city, county, and State of New York, have invented certain new and useful Improvements in Valves, of which the following is a full and clear description.

My invention relates to puppet valves for fluid pressure engines, particularly to exhaust valves for internal combustion engines.

These latter valves are apt to fail in their functions because of foreign matter finding lodgment between the valve and its seat, and carbon fouling the outside and edges of the valves.

One object of this invention is to remove any foreign matter forthwith and to this end a relative movement between the valve and its seat is provided.

To avoid fouling of the outer surface of the valve, without however permitting it to become unduly hot, I provide a passage through the exhaust valve and circulate a cooling fluid through it without reducing the temperature of the valve as a whole, permitting the valve head to rise to a sufficient heat to prevent the accumulation of carbon and keeping it at a temperature low enough to avoid warping or the valve stem from overheating.

By way of illustration I have described in the following specification and shown in the accompanying drawings, my invention as applied to an exhaust valve of the puppet type in an internal combustion engine. It is to be understood, however, that the invention is broader than the particular use shown here and is capable of many variations.

In the drawings

Figure 1 represents in longitudinal section one cylinder of a four cycle internal combustion engine, equipped with my improved exhaust valve.

Fig. 2 is a top view of the same.

Fig. 3 is a longitudinal section, on a larger scale, of the exhaust valve.

Fig. 4 and 5 are similar views of the exhaust valve at successively later periods of the cycle, and

Fig. 6 is a cross section on the line A—B of Fig. 1.

Figs. 7 and 8 show modifications.

Referring more particularly to the drawings, 2 represents a cylinder, 3 its crank housing, 4 a crank, 5 a piston and 6 a connecting rod of a four cycle engine of usual construction; 7 and 8 are the conventional half-time gears, coöperating with cam 9 on shaft 10, roll 26, push rod 27 and rocker 25 to produce the usual four cycle motion of exhaust valve 12. In addition to this motion two other, but slight motions, are produced by cam 9 as will be shown later. At 11 is shown an automatic inlet valve of the puppet type with a 45° seat.

The exhaust valve 12 is also of the puppet type but is flat seated and here eccentric to its seat as shown by the overhang at 13, the valve seat 14 being slightly elevated and narrow. Exhaust valve 12 is held to its seat by spring 15 anchored to a bracket 16, which also supports the pivot of rocker 25. A stirrup 19 mounted loosely upon screw head 20 connects spring 15 with valve stem 23. With this arrangement rotation of the valve stem 23 with respect to the stirrup 19 is permitted, the rotating means comprising pawl 21 with a spring 32, a back stop 33 and pivoted at 24; crown ratchet wheel 22 is rigidly secured to the valve stem 23. Further details of this movement will be described later.

Valve stem 23 is hollow, the passage 28 communicating at one end with the space within the cylinder 2 and through the ports 28' with the atmosphere. Sleeve valve 29 hung by curved link 30 at 31 to rocker 25 is adapted to close the ports 28' during the compression, explosion and scavenging strokes, the cam 9 being formed to produce this motion without interfering with the "four cycle" movement of the exhaust valve 12. It will be seen that on the suction stroke of the piston, ports 28' being open, a current of air will be drawn through the passage 28,

producing a local drop in temperature in valve 12, but ports 28' are kept closed during the compression and explosion strokes of the engine. The passage 28 may be readily cleaned by removing the screw plug 20, without taking apart the exhaust valve and associated parts.

The order of the movements of rocker 25 are as follows: The position shown in Fig. 1 10 shows the beginning of the suction stroke; piston 5 beginning its downward travel; valves 11 and 12 are shown closed, and ports 28' in hollow stem of exhaust valve 12 are open, sleeve valve 29 being held high by 15 means of link 30 and rocker 25, to this end, so that air will enter by way of ports 28' into the combustion chamber, thereby keeping valve 12 at such a point of heat that no carbon can form on it; at the same time, 20 by way of control cock 37 and check-valve 36, fuel has entered by way of igniter 34 with its spark plugs 35 and 35' and by means of the vacuum created by the down-going piston, turned into a gas. A little later the 25 automatic inlet valve 11 opens, admitting air . . . to close again near the end of the stroke of piston 5. Next, sleeve valve 29 is lowered, closing ports 28', because of a suitable formation of cam 9, by way of roller 26, 30 rod 27, rocker 25 and link 30. During the following compression and working strokes all ports remain closed. The "charge" is 35 ignited by means of spark plug 35 with the usual electric connection at the conventional time. At about the end of the working stroke because of suitable contour of cam 9, rocker 25 approaches head 20 of exhaust valve 12, thereby engaging pawl 21 with ratchet wheel 22, and the rocker and 40 pawl straighten out during the approach of rocker 25 to head 20, thereby rotating exhaust valve 12 without however lifting it off its seat 14, the position then being as shown in Fig. 4.

45 This produces a shearing action at the moment before lifting the valve when it is under considerable pressure, removing any foreign matter which may have found lodgment upon either valve or valve seat; to this 50 end, as shown in Figs. 1 to 4 and 6, the valve stem 23 is located eccentric to its seat and overhanging at 13.

A further move of rocker 25 opens exhaust valve 12 fully as shown in Fig. 5, to 55 again close at the end of the scavenging stroke in usual manner ready to repeat.

Although a valve, eccentric to its seat, has been shown at Fig. 6, another method can be used in which an overhanging and shearing 60 action is shown in Fig. 7, the valve seat 14 being oval; in this case the valve stem may be central to the valve seat. The valve stem could be also guided in an eccentric bushing, which could be either rotated or moved to

and fro without departing from the spirit 65 of this invention, as shown in Fig. 8, in which lever 38 may be moved in any convenient manner.

I claim:

1. In an engine, a valve seat and a puppet valve having a flat seating surface and rotatable about an axis spaced unequally from points around the inner edge of said valve seat, said puppet valve being adapted by rotation to scrape its contact surface laterally across said valve seat. 75
2. In an engine, the combination of a flat seated puppet valve, the seat constructed to provide an overhang for said valve, and means for permitting a relative movement 80 of the contacting surfaces to produce a shearing action.
3. In an engine, the combination of a flat faced puppet valve; a narrow and raised seat therefor with the valve head overhanging said seat and means for rotating said valve while on its seat. 85
4. In an engine, a puppet valve provided with a passage, said passage affording a means for equalizing fluid pressure on the 90 two sides of the valve to provide a local reduction in temperature in said valve to avoid overheating, and means for controlling said passage, said means being independent of the movement of the valve. 95
5. In an engine, the combination of a puppet valve provided with a passage throughout its stem and head and means for affording a movement of air through said passage. 100
6. In an engine, the combination of a puppet valve provided with a passage through its stem and head and means for affording a movement of a fluid through 105 said passage, means for keeping such movement in one direction for the purpose described, said means being independent of the movements of the valve.
7. In an engine, the combination of a puppet valve provided with a passage through its stem and means for affording a movement of fluid through such stem and means for keeping such movement in one direction 110 for the purpose described.
8. In an internal combustion engine, the combination of a puppet valve provided with a passage through its stem and head to allow the movement of a fluid through said passage and a sleeve valve opening said passage during the suction stroke of said engine. 115
9. In mechanism of the character described, the combination of a puppet valve having a passage through its stem and head to permit the passage of cooling fluid and means for causing the passage of said fluid when the pressures on the two sides of the 120 valve are unbalanced, said means being independent of the movement of said valve. 125
10. In mechanism of the character de-

scribed, the combination of a puppet valve having a channel through stem and head to permit a flow of fluid, and means for closing said passage before the pressure within the 5 cylinder exceeds the external pressure, said means including a sleeve valve sliding upon said valve stem and independent of said valve.

11. In mechanism of the character de-
scribed, the combination of a puppet valve
having a channel to afford a passage for a
fluid, and an automatic means for keeping

the fluid passing through said channel uni-directional for the purpose described.

12. In mechanism of the character de- 15
scribed, a puppet valve having a hollow ex-
tending through it, stem and head, and hav-
ing means for permitting cleaning of such
hollows without removing the valve.
